UNITED STATES PATENT OFFICE.

TIBURCE CATALA, OF ENGLEWOOD CLIFFS, NEW JERSEY.

GILDING APPARATUS.

Application filed June 11, 1923. Serial No. 644,770.

To all whom it may concern:

Be it known that I, TIBURCE CATALA, a citizen of the United States, and a resident of Englewood Cliffs, in the county of Bergen and State of New Jersey, have invented a new and Improved Gilding Apparatus, of which the following is a full, clear, and exact description.

This invention relates to a gilding apparatus, and an object of the invention is to provide a simple, efficient, durable apparatus whereby embossing on surfaces, such as leather, in gold and similar substances can be very simply and easily achieved with a minimum of labor and skill required in the operation.

Another object of the invention concerns the provision of means whereby the apparatus is adjustable for use in connection with many different kinds of gilding operations so that articles of all sorts can be simply and easily embossed.

The invention is illustrated in the drawings, of which—

25 Figure 1 is a plan view of the device with a portion broken away to show the manner in which the work supporting table can be adjusted;

30 Fig. 2 is a section taken on the line 2—2 of Fig. 1;

Fig. 3 is a section taken on the line 3—3 of Fig. 1;

Fig. 4 is a section taken on the line 4—4 of Fig. 2; and

35 Fig. 5 is a sectional view taken through a modified form of the pressure roller.

The form of the invention shown in the drawings is a preferred form, although it is understood that modifications in the construction and arrangement of the parts and in the character of the materials used may be adapted without departing from the spirit of the invention.

The preferred form of the invention as shown in the drawings comprises a table 1 which along one side is provided with grooves adapted to receive ribs 2 formed on a vertically slidable work support table 3. This table is adjustable so as to bring the 45 upper surface of any piece of work mounted thereon adjacent the edge of an impressing roller or disk 4 which is loosely mounted on a fixed shaft 5. Disposed beneath this disk or roller 4 is a burner portion and gas 50 burner 6 connected by suitable piping 7 to a source of supply, and surrounding this

burner and extending up beneath the disk or roller 4 is a shield 7^a to confine the heat from the burner to the under surface of the roller or disk 4 and not permit it to spread to other parts of the apparatus unduly. The embracing disk 4 is provided with a handle 8 whereby it can be manually operated.

In the normal operation of the device, however, this impressing roller is moved to 65 contact with a pressure roller 9 mounted loosely on a shaft 10. The shaft 10 is mounted on a slidable block 11 sliding in a groove 12 formed in the table 1 and is normally pressed forward by a spring 13 extending between the end of the groove and the end of the block 11. This spring surrounds a pin 14 fastened to the table and extending into a bar 15 in the block 11. A cord or other connection such as 16 is 70 fastened to the shaft 10 and provided at its other end with a hook or similar device 17 whereby it may be engaged with a fixed member, such as a nail or screw 18, so as to hold the shaft 10 in its rearward or retracted 75 position against the action of spring 13, thereby withdrawing the pressure roller 9 from contact embossing roller 4.

Also, loosely mounted on shafts 19 and 20 fixed to the table top in suitable slots such as 21 and 22 for adjustment, are reels or supports 23 and 24. These reels or supports are adapted to support rolls of strip material, such as 25 and 26. This strip material is preferably a strip of any suitable fabric, such as paper, bearing on one side a layer of gold leaf or similar material. This strip, as shown in Fig. 1, passes between the pressure roller 9 and the embossing roller 4, and by reason of the fact that the embossing roller 4 is hot the gold leaf will be taken off the strip and carried by the embossing roller to the material to be embossed. The embossing roller may be moved either by manual operation of the handle 8 or by direct 100 contact between the embossing roller 4 and the article to be embossed, which can be slid along the table or support 3 and in this movement cause the rotation of the embossing roller.

It is, of course, understood that the required pressure between the rollers 4 and 9 is achieved by the spring 13, and that the pressure roller can be turned back at any time to relieve this pressure. The table 3 110 can be adjusted at any desired height, as above mentioned and the reels 23 and 24

can be adjusted as desired. A scraper such as 27 is mounted on a suitable bracket 28 to bear against the edge of the impression roller after said roller has come in contact with the article to be embossed, so as to scrape off the remaining material.

As shown in Fig. 5, the pressure roller is preferably formed of a plurality of flat disks 29 of any suitable material which can be built up in any desired manner to the desired height, depending upon the size of the strip which is to be run between this pressure roller and the impression or embossing roller. This pressure roller 10 prises a flat plate or support 30, the disks 29, a top plate 31, and a tightening or clamping screw 32 extending between the top plate 31 and the bottom support 30. Preferably this form of pressure roller is held on to its 20 shaft by means of a collar 33.

What I claim is:—

1. A gilding apparatus which includes an embossing roller having a design formed along its periphery, said roller loosely 25 mounted for rotation, a heating means disposed beneath said roller, and a shield surrounding said heating means and extending up to a point substantially closed to the under surface of the roller whereby the heat 30 of the burner will be confined.

2. A gilding apparatus which includes a

support, an embossing roller loosely mounted thereon for rotation, a pressure roller mounted on said support and bearing against the edge of the embossing roller, 35 means for heating said embossing roller, means for feeding a strip of material bearing gold leaf between the pressure roller and the embossing roller, and an adjustable platform adjacent the embossing roller 40 adapted to support the work, whereby said work can be moved along the work support in contact with the embossing roller to move the same and to receive an impression thereon in gold leaf.

3. A gilding apparatus which includes an embossing roller, a pressure roller bearing thereagainst, a pair of reels adapted to support rolls of strip material bearing gold leaf, said strip adapted to be passed between the two rollers, means for heating said embossing roller whereby it will pick the gold leaf from the strip, and an adjustable work support adjacent the embossing roller capable of supporting the workpiece, 55 which can be moved therealong to contact with the embossing roller to rotate the same and to receive the gold leaf embossed thereon in a design carried on the edge of the roller.

TIBURCE CATALA.
